US00D769813S

(12) **United States Design Patent** (10) Patent No.: **US D769,813 S**
(45) Date of Patent: **** Oct. 25, 2016**

(54) **RECHARGEABLE BATTERY DEVICE**

(71) Applicant: **Limefuel, LLC**, Boulder, CO (US)

(72) Inventor: **Paul Lin**, Boulder, CO (US)

(73) Assignee: **Limefuel, LLC**, Boulder, CO (US)

(**) Term: **15 Years**

(21) Appl. No.: **29/548,461**

(22) Filed: **Dec. 14, 2015**

(57) **CLAIM**

The ornamental design for a rechargeable battery device, as shown and described.

DESCRIPTION

FIG. 1 is a front perspective view of the rechargeable battery device;

FIG. 2 is a rear perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

The broken lines showing a rechargeable battery device are included for the purpose of illustrating environment and form no part of the claimed design.
